UNITED STATES PATENT OFFICE.

HENRY D. POWNALL, OF CANTON, OHIO.

ARTIFICIAL-ICE-MAKING APPARATUS.

Application filed May 4, 1921. Serial No. 466,759.

To all whom it may concern:

Be it known that I, HENRY D. POWNALL, citizen of the United States, residing at Canton, in the county of Stark and State of Ohio, have invented certain new and useful Improvements in Artificial-Ice-Making Apparatus, of which the following is a specification.

My invention relates to improvements in artificial ice making apparatus. One of its objects is to provide improved means to feed cold or warm brine to the respective freezing tank units to freeze and release the ice blocks. Another object is to avoid projection of valve stems or other objects above the floor of the tank room. Another object is to provide improved valve mechanism adapted to reliably control the brine flow and to avoid liability of the valve mechanism being rendered inoperative from the lodging of obstruction therein, and to provide for the convenient removal of obstructions and maintenance of the valves in operative condition. Another object is to provide improved and simple valve mechanism, and means to connect the same to the tanks and conduits. Another object is to provide improved means to avoid fracturing the ice blocks by subjecting the ice molds to rapid changes of temperature or local changes of temperature or any considerable range of temperature. Another object is to eliminate all stuffing boxes and the packing or leakage thereof on the brine circulatory system, or the introduction of air or gas into such system to interfere with the action of the circulating pump. Another object is to secure quickly actuated valves. My invention also comprises certain details of form, combination and arrangement, all of which will be fully set forth in the description of the accompanying drawings, in which:

Fig. 1 is a diagrammatic plan of a portion of an artificial refrigerating apparatus embodying my improvements.

Fig. 2 is a plan of the inside of one end of one of the freezing tank units with the warm and cool brine inlet and exit valves mounted thereon.

Fig. 3 is an enlarged inside elevation of one of the warm brine inlet and exit valves and also showing the relation of the valve stem to the tank floor.

Fig. 4 is a central vertical section through one of the warm brine valves on line 4—4 of Fig. 2.

Fig. 5, is a horizontal section through one of the warm brine valves on line 5—5 of Fig. 3.

The accompanying drawings illustrate the preferred embodiment of my invention in which 14 represents a brine cooler tank of an artificial ice making apparatus, divided by an L-shaped partition 140 into a brine receiving compartment 14' and a brine distributing compartment 14''. A brine circulating propeller 15 forces the brine under a head of a few inches from the receiving compartment through a series of flues or channels, where the brine is cooled by a direct expansion system 16 into the brine distributing compartment. A plurality of freezing tank units 17 are employed on both sides of the brine cooler if desired, which are substantially duplicates of each other and in each of which are a series of cans or ice molds 18, mounted therein in a substantially permanent manner, so that all the cans of one unit are filled with raw water through ports 18' at their bottoms at one operation, and all the blocks of ice are released from the ice molds 18 at one operation by displacing the cool brine with a warmer brine from a warm brine coil 20, thus gradually warming the cold brine by circulating the same through the coil 20. The tank 19 contains a body of fresh water sufficient to fill all of the cans in any one of the freezing tanks and has submerged therein a coil of pipe 20, through which cold brine, taken from one of the freezing tanks in which the ice is completely frozen and ready to be harvested through the pipe 25, is circulated to warm or partially warm the brine in its passage through the pipe 20. The passage of the raw water through the tank 19 and raw water conduit 19' reduces the temperature of the raw water before it enters the ice cans 18 to near its freezing point, while in turn the brine passing through the coil 20 has its temperature correspondingly elevated and thereby adapts the raw water from the tank 19 to be economically employed to fill the ice cans and the warm brine from the coil 20 to be economically employed in one of the freezing tanks 17 surrounding the ice cans to release the ice from the cans in the respective freezing tanks and without liability to subject the ice in the molds to such sudden changes in temperature as to fracture the ice in the ice cans. A supply pipe 21 leads from the exit end of the coil 20 with a branch

pipe 22 to each freezing tank and a circulating pump 23 is included in the circuit. The warm brine returns to the coil 20 from the respective freezing tanks through branch 5 pipes 24 and main return pipe 25.

In practice it is designed to have relatively large brine supply and return conduits 30 and 31 leading from the brine cooler to the respective freezing tanks in pairs to rapidly 10 supply a relatively large volume of cold brine under a relatively low head or pressure and to take back to the brine cooler a corresponding quantity of brine not quite but nearly as cold as that flowing 15 from the brine cooler, thereby maintaining a rapid exchange and circulatory flow which serves to keep the cold brine in all parts of the freezing tanks at substantially uniform temperature, and avoids pockets and localities 20 therein of higher temperature than the general average. One or more partitions 17 are provided in the respective freezing tanks, to insure a uniform circuitous flow of brine through the freezing tanks and about the 25 ice cans therein as indicated by arrows in Fig. 1.

In order to control the flow of cold brine to and from said respective freezing tanks, I provided an intake valve frame 26 and 30 an exit valve frame 27 adapted to be attached by cap screws 28 to one end plate 29 of each of the freezing tanks 17 opposite a perforation in said plate 29. In order to conveniently couple the cold brine conduits 35 30 and 31 leading from the brine cooler to the respective freezing tanks, to the wall 29 of said tanks, and to the valve casings at the same time with leak proof joints, I provide collars 32 outside of the plate 29 and 40 stuffing box recesses with packing therein in the valve casings, so that when the cap screws are drawn up tight the packing is compressed and forms leak proof joints about the unthreaded ends of the conduits 45 30 and 31, and also a leak proof joint against leakage of brine past the valve between the plate 29 and the valve casing. Each valve casing is provided with a valve seat 34 adapted to be machined or ground 50 to a uniform plane surface. Each casing is also provided with ways or guides 35 which serve to guide a disk shaped gate valve 36 to and from its seat 34. To the center of each valve is pivotally attached 55 one end of a link 37, the opposite end of which link is pivotally connected to a lever 38. The lever 38 is pivotally connected to the valve casing at 38' and is guided by a lug 35' and its upper end extends upwardly 60 to the floor of the tank room, or slightly below said floor where it is perforated so as to be engaged by the operator by means of a hooked lever to either open or close the valve, thereby enabling said valves to be 65 operated without presenting any valve

stems or other obstructions above the floor of the tank room. The force exerted by the lever and link upon the gate valve is always substantially in direct line to force the valve over its valve seat or away therefrom. A pair of screws 40, having conical inner ends are threaded through projections 41 on the valve casings, and as the gate valves 36 are forced by the levers over their seats, the beveled edges of the gate valves are engaged by the conical ends of screws 40 to force the gate valves down tightly upon their seats to form a leak proof joint therewith. The screws 40 may be closely adjusted, and locked by set-screws 41' so as to engage the valve at such a position of the valve as to force the valve firmly down upon its seat to produce a leak proof joint. It will be noted that the valve seats and valves open into the freezing tank in such a manner that any solid or foreign matter carried in the liquid is free to fall away from or be brushed away from the valve seat by the valve, and that any such solid or foreign matter tends to fall away from the valve and thus leave the valve and its seat at all times clean and free to form a leak proof joint. Said valves are also readily accessible by hand or by means of a tool to detach any foreign matter that may obstruct or render them inoperative. The screws 40 are adapted to be adjusted from time to time so that their conical points will engage and seat the valve at the correct position of the valve, and when so adjusted are adapted to 100 be locked to their adjusted positions by means of set-screws 41'.

The valve casing 27 of the brine exit conduit 31 differs from the casing 26 of the brine inlet conduit 30 in that an overflow port 44 is provided therein to conduct either cold brine or warm brine by overflow method to the brine cooler even though the exit valve 36 be left closed. The exit valve 27 and conduit 31 are located near the top of the freezing tank and the entrance of the overflow port 44 is a sufficient distance above the valve so that the valve remains continuously submerged. Thus even though the cold brine inlet valve may be opened accidentally without also opening the cold brine exit valve, or in the event that the warm brine inlet valve be opened without at the same time opening the warm brine exit valve, the brine will not accumulate 115 in any one of the freezing tanks to such an extent as to overflow into the ice molds and damage the partially frozen or finished ice cakes, or get into the fresh water conduits or overflow the freezing tank and injure its insulation, or the building in which it is located. Instead of causing a brine overflow or other injury in the event of the improper regulation of the brine conduit valves of any one of said freezing tank 120 125 130

units, the brine will be maintained at a uniform surface level in such freezing tank unit, without liability to overflow into the ice molds, or to overflow to the exterior of such freezing tank unit, and the excess brine will be conducted from said tank through the overflow port 44 to the brine cooler tank where it will find its level by reacting upon the head and distribution of the entire brine circulation system of which the brine in one freezing tank is a relatively small fraction.

When the fresh water in the ice molds of any one freezing tank has been completely frozen into blocks of ice, the cold brine circulating valves 36 thereof are closed and the warm brine valves 46 and 47 to that freezing tank unit are opened, thereby slowly removing cold brine and replacing it with warmer brine in such manner as to release the blocks of ice from the molds without so suddenly applying warm brine as to cause the ice blocks to become fractured. After the ice blocks have been removed the ice molds are refilled with fresh water, the warm brine circulation through that freezing tank unit is cut off and the valves 36 opened to re-establish a circulation of cold brine until the ice molds are again filled with ice.

In order that the warm brine valves 46 and 47 may be conveniently applied to the tanks, connected to the branch warm brine conduits, actuated without projections above the tank floor, readily freed and kept free from obstruction, and prevented from discharging warm brine so as to fracture the ice, I secure warm brine valve casings 50 by means of flanges 51 and bolts or rivets 51' directly to the inner faces of the freezing tanks, and provide threaded flanges 52 on said valve casings into which the ends of the branch warm brine conduits 22 and 24 are threaded. Each of said valve casings is provided with a through port 53 for the passage of the warm brine, and a deflector 54 to divert or deflect the current of warm brine from opposite sides laterally, and thus mixing the incoming warm brine with the cooler brine in the tank to even its temperature and avoid a direct current of warm brine being locally applied to one of the cans so as to fracture the ice blocks therein.

Each valve casing 50 is provided with a tapered bore or recess vertically disposed to receive a correspondingly tapered valve or cock 46 or 47 having a brine port 56 therein to be turned so as to register with the casting port 53 when the valve is open, and to be adjusted to a position transversely to the port 53 when the valve is closed. The tapered valves 46 and 47 are held in place in the valve casings by gravity and are provided with the valve stems 57 projecting up to recesses 58 cut in the tank lid or tank floor 59, where said valve rods are provided with

slots 60 to receive a detachable manually operable key to open and close said valves 46 and 47. Also in the event of obstruction entering one of the valves, 46 or 47, it and its valve rod may be lifted from the casing 70 and the obstruction manually removed and the valve replaced without seriously interrupting the operation of the apparatus.

Each of the valves 46 and 47 being at all times below the level of the brine in the freezing tank they require no stuffing boxes or packing and it is impossible for air to enter the warm brine circuit to become pocketed or trapped therein or to interfere with the brine flow, or to interfere with the action and efficiency of the circulating pump 23.

The warm brine regulating and distributing apparatus herein illustrated and described is capable of considerable modification without departing from the principle of my invention.

What I claim is:—

1. In combination with the freezing tank of an artificial ice making apparatus, a heat exchange member through separate compartments of which the raw water and brine are circulated so that the raw water leaves the exchange member cooler than when it entered and the brine leaves the exchange member warmer than when it entered, a brine supply conduit leading from said exchange member to said freezing tank and a brine return conduit leading from the freezing tank to the exchange member, means to circulate brine to and from said freezing tank, a valve casing attached to the inside of the freezing tank wall and to which the warm brine inlet conduit is attached, said valve casing being provided with a brine inlet port and a warm brine deflector to deflect the incoming warm brine inside the tank and mix the warm brine with the brine in the freezing tank, a valve removably seated in said valve casing and provided with a valve stem projecting upwardly within the freezing tank to near the top of the said freezing tank.

2. In combination with the freezing tank of an artificial ice making apparatus, a heat exchange member through separate compartments of which the raw water and brine are circulated so that the raw water leaves the exchange member cooler than when it entered and the brine leaves the exchange member warmer than when it entered, a brine supply conduit leading from said heat exchange member to said freezing tank and a brine return conduit leading from the freezing tank to said heat exchange member, means to circulate brine from said heat exchange member to said freezing tank, a valve casing attached to the inside of the freezing tank wall at the terminus of said brine inlet conduit, said valve casing being

4
provided with a brine inlet port and warm
brine deflector to deflect the incoming warm
brine inside the tank and mix it with the
brine in the tank, a valve seated in said valve
casing inside of freezing tank adjustable to
open and close the port in said valve casing,
and means to actuate said valve.

5 3. In combination with the freezing tank
of an artificial ice machine, a heat exchange
10 member through separate compartments of
which the raw water and brine are circu-
lated so that the raw water leaves the ex-
change member cooler than when it entered
and the brine leaves the exchange member
15 warmer than when it entered, a brine sup-
ply conduit leading from said heat exchange
member to said freezing tank, a brine return
conduit leading from said freezing tank to
said heat exchange member, separate valve
20 casings attached to the inner face of the
freezing tank at the terminals respectively
of said supply conduit and said brine re-
turn conduit, said valve casings being pro-
vided with ports for the passage of brine,
25 and recesses to receive valves to control said
ports, valves removably seated in the re-
cesses in said valve casings, and valve stems
extending upwardly through said freezing
tank and serving to adjust said valves in
30 their casings from open to closed position,
and also to lift said valves from and re-
turn them to their position in said valve
casings.

35 4. In combination with the freezing tank
of an artificial ice machine, a warm brine
supply conduit leading to said freezing
tank, a valve casing at the terminus of said
conduit attached to the inner face of one of
40 the side walls of the said tank and provided
with a brine port, a tapered recess to receive
a valve and a deflector to deflect the current
of warm brine entering the brine tank and
to mix the warm brine with the brine in
45 the freezing tank before it comes in contact
with the ice cans, a tapered valve to be
seated in the recess in said valve casing, and
adjustable to open and close the brine port
in the valve casing, and means to actuate
50 said valve.

55 5. In combination with the freezing tank
of an artificial ice making machine, a warm
brine supply conduit leading to said freez-
ing tank, a valve casing located at the termi-
nus of said conduit and below the surface
55 of brine in said freezing tank attached to
the inner face of one of the side walls of

said tank and provided with a brine port, a
tapered recess to receive a valve and de-
flector to deflect the current of warm brine
entering the freezing tank and to mix the 60
warm brine with the brine in said freezing
tank before it comes in contact with the ice
cans, a tapered valve to seat in the recess
of said valve casing and adjustable to open
65 and close the brine port in the valve casing,
a valve stem projecting upwardly from said
valve to near the top of the freezing tank
and adapted to rotatably actuate said valve
and also to lifting said valve from its seat
70 and replacing it therein.

75 6. In combination with the freezing tank
of an artificial ice making machine, a warm
brine supply conduit, a warm brine return
conduit, valve casings at the terminals of
said respective warm brine conduits, at-
80 tached to the inner face of one of the side
walls of said freezing tank and provided
with brine ports and tapered recesses to
receive the valves to control the flow of
warm brine to and from said tank, tapered
85 valves respectively seated in recesses in said
valve casings and removable therefrom and
valve stems projecting upwardly from said
respective valves to near the top of the tank
and adapted to rotatably adjust said valves,
and to remove said valves from their casings
and to replace them therein.

90 7. In combination with a freezing tank
provided with a plurality of ice cans and a
heat exchange member through the separate
compartments of which the raw water and
brine are circulated so that the raw water
95 leaves the exchange member cooler than
when it entered and the brine leaves the ex-
change member warmer than when it en-
tered, a brine supply conduit leading from
the exchange member to said freezing tank
100 and a brine return conduit leading from the
freezing tank to the exchange member,
means to circulate brine to and from said
freezing tank and inlet and exit valves at
the terminals of said brine conduits to con-
105 trol the flow of brine to and from said heat
exchange member, said valves being located
within said freezing tank and below the sur-
face of the brine therein to avoid packing
of said valves and leakage of brine from
110 said valves or the introduction of air into
said brine circulating conduits.

In testimony whereof I have affixed my
signature.

HENRY D. POWNALL.
